CLAIM

The ornamental design for a sous vide cooking stick, as shown and described.

DESCRIPTION

FIG. 1 is a left upper perspective view of a sous vide cooking stick design showing our new design.

FIG. 2 is a right lower perspective view of a sous vide cooking stick.

FIG. 3 is a front view of a sous vide cooking stick.

FIG. 4 is a rear view of a sous vide cooking stick.

FIG. 5 is a left side view of a sous vide cooking stick.

FIG. 6 is a right side view of a sous vide cooking stick.

FIG. 7 is a top view of a sous vide cooking stick; and,

FIG. 8 is a bottom view of a sous vide cooking stick.

Any shading and cross-hatching are not features of the design but are utilized to illustrate the surface contours of the sous vide cooking stick design in the drawings.
